UNITED STATES PATENT OFFICE.

FREDERICK T. SPATH, OF MINNEAPOLIS, MINNESOTA.

RAILROAD TIE.

Application filed November 8, 1924. Serial No. 748,561.

To all whom it may concern:

Be it known that I, FREDERICK T. SPATH, a citizen of the United States, residing at Minneapolis, in the county of Hennepin and

5 State of Minnesota, have invented certain new and useful Improvements in Railroad Ties; and I do hereby declare the following to be a full, clear, and exact description of the invention, such as will enable others 10 skilled in the art to which it appertains to make and use the same.

This invention relates to railroad ties constructed entirely of metal, preferably rolled steel or malleable iron.

15 This invention has for its object to provide a simple but highly efficient metallic railroad tie constructed from a minimum of material to give the maximum of strength and efficiency.

20 It is an additional object in such a tie to provide means thereon for preventing lateral and longitudinal displacement or "creeping" and to also prevent the roadbed between the ends of the tie from washing 25 out.

It is an additional object to resiliently reinforce a tie at the portions thereon to which the rails are secured.

To these ends, generally stated, the invention 30 consists of the novel devices and combinations of devices herein described and set forth in the claims.

The invention is illustrated in the accompanying drawings, wherein like notations 35 refer to similar parts throughout the several views, and in which,

Fig. 1 is an elevation of the tie applied to the road bed;

Fig. 2 is a plan view of the same, with 40 some parts broken away; and

Fig. 3 is a cross section taken on the line 3—3 of Fig. 1.

In the preferred form of the invention illustrated, an elongated body member is 45 designated by the numeral 4, constructed of rolled steel or malleable iron, of relatively thin cross section, having downwardly and inwardly curved end portions 5, of hook-shaped cross section. These hook-shaped ends have aligned substantially rectangular slots in the opposite sides thereof, through which blade-shaped stakes 6 are 50 adapted to be passed or driven and further driven into the roadbed to firmly secure the tie against "creeping" or lateral displacement. A plurality of rugged clips

7 are mounted on said body member 4 and secured thereto by headed bolts 8 and adapted to engage the flanges of rails 9, at opposite sides thereof, to secure said rails 60 to the top of body member 4. A pair of U-shaped reinforcing members or chairs 10 are riveted or otherwise secured to the bottom of body member 4, directly beneath the rails 9. These U-shaped members are 65 constructed of, preferably, rolled steel having a considerable degree of resiliency.

The ties are set in the roadbed with the body member 4 supported on the top thereof and with the hook-shaped end portions 5 70 gripping the central portion of the roadbed at either end of the tie. In installing the tie, the roadbed is cut down to accommodate the depending portions thereof, including the hook shaped ends 5 and the U-shaped members 10. The tie is then laid in proper position and said members packed with the sand or dirt and the road bed then thoroughly tamped about the ends and sides of said tie. The chairs 10 are also preferably filled with sand or roadbed material and the stakes 6 are driven through the apertures in the ends 5 into the roadbed. The clips 7 are then clamped down 75 against the flanges of the rails to firmly secure the same to the top of body member 4. The stakes 6 should be about two and one-half feet in length.

It will be seen from the above description that the hook-shaped extremities 5, being inwardly curved, will grip the central portion of the roadbed therebetween and prevent the same from washing out during rain, and also preventing any longitudinal slipping of the tie. The chairs 10 reinforce the portions of the body member 4, which the rails traverse, and also assist to prevent longitudinal movement of the tie, giving the desired elasticity to the rail and reinforcing the same where the greatest strain is imposed.

The blade-shaped stakes 6, rigidly held in proper position in the slots formed in the hook-shaped ends 5, prevent lateral displacement or "creeping" of the tie. The hook-shaped ends 5, therefore, not only afford gripping claws or anchors but also permit the stakes 6 to be rigidly braced, whereby it will be practically impossible for vibration from passing trains to work the stakes loose.

In repairing the rails, the clips may be

readily loosened by unscrewing the nuts on bolts 8, and if it is desired to replace the bolts, this may be readily effected by digging out the dirt in chair 10 from the side 5 of the rail, and inserting a new bolt from the bottom of the body member 4.

It will be seen from the above description, that applicant has provided a rugged and highly efficient metallic railroad tie con- 10

structed on sound scientific principles. Means are provided for preventing both longitudinal and lateral displacement of the tie, and also for preventing the dirt or sand 15 between the ends thereof from washing away. The material used is little and the entire tie may be manufactured at small cost.

It will, of course, be understood that various changes may be made in the form, details and arrangement of parts, without 20 departing from the scope of applicant's in-vention.

What is claimed is:—

1. A railroad tie comprising an elongated body member having means thereon for se- 25 curing rails thereto and having its extremi-ties extended downwardly for some dis-tance and inwardly to constitute anchoring and supporting members for said tie, the outer surfaces of said downwardly extend-ing portion constituting the extremities of 30 the tie.

2. A railroad tie comprising an elongated body member of relatively thin cross-sec-tion having means thereon for securing rails 35 thereto and having depending inwardly curved extremities constituting anchoring or supporting members for said tie and adapt-ed to grip the road bed and present smooth rounded ends at the top of said road.

40 3. A railroad tie comprising an elongated

body member having means thereon for se-curing rails thereto and having depending inwardly extending anchoring members ad-jacent the ends thereof and members carried by said anchoring members adapted to ex-tend into the road bed substantially parallel with the longitudinal edges of said body member to hold the tie against lateral dis-placement.

4. A metallic railroad tie comprising an 50 elongated body member having means thereon for securing rails thereto and having end portions of hook-shaped cross section pro-vided with aligned apertures in the oppo-site sides of said hook-shaped ends, and 55 stakes adapted to be driven through said apertures into the roadbed to secure said tie against lateral displacement.

5. A metallic railroad tie comprising an elongated body member of relatively thin 60 material having means thereon for securing rails thereto and terminating in hook-shaped portions adapted to grip the road-bed and prevent longitudinal displacement of said tie, said hook-shaped members hav-ing aligned slots on the opposite sides there-of, and a pair of blade-like stakes adapted to pass through said slots and be driven into said roadbed to hold the tie against 65 lateral displacement.

6. A metallic railroad tie comprising an elongated body member of relatively thin material having means thereon for securing rails thereto, U-shaped reinforcing members 75 secured to said body member beneath said rail-securing means, and hook-shaped anchoring means on the extremities of said body member.

In testimony whereof I affix my signature.
FREDERICK T. SPATH.
